UNITED STATES PATENT OFFICE.

EDWARD A. MARYE, OF BON AIR, VIRGINIA.

DOWEL CONCRETE JOINT.

Application filed June 3, 1924. Serial No. 717,528.

To all whom it may concern:

Be it known that I, EDWARD A. MARYE, a citizen of the United States, residing at Bon Air, in the county of Chesterfield and State 5 of Virginia, have invented certain new and useful Improvements in Dowel Concrete Joints, of which the following is a specification.

This invention relates to concrete structures, and it relates particularly to dowel joints for sustaining in alignment separately formed adjacent sections of such structures.

While hereinafter the invention is particularly described as applied to roadbeds, it is 15 not intended thereby to limit the scope of the invention. It may with advantage be applied to many other concrete constructions where adjacent portions are separately formed, and where it is necessary that such 20 portions be maintained in predetermined relation to each other.

The general mode of applying dowel rods in constructions of the kind referred to is to embed portions of the rods in a section 25 of the structure with a portion, generally one-half, of the rods projecting therefrom, and, when the material of the first section has sufficiently set, the rods are withdrawn a short distance for the purpose of leaving 30 chambers adjacent to the inner ends of the rods in which such ends may move when they or slabs in which they are contained, expand or contract when affected by changes in climatic conditions. Theoretically this 35 method is correct, but in practice it is by no means reliable. Frequently when the rods are withdrawn the apertures formed are more or less filled in by the falling into them of the material of the structure. The most 40 frequent difficulty encountered, however, is the failure on the part of workmen to withdraw the rods, and the latter being embedded at their inner ends, their positions cannot accurately be ascertained, particularly 45 after the composition in which they are placed becomes set. Besides, workmen necessarily remain idle until the material sets sufficiently to allow withdrawal of the rods with the assurance that an open space 50 will be formed adjacent to their inner ends.

The object of the present invention is to provide a dowel rod provided with means of such form that it may rapidly be put into position for use without especial care, and that the facility for expansion or contraction 55 of the rod or slabs in which it is con-

tained shall be insured under all conditions. A further object is to provide a dowel rod for the specified purpose which can be placed in position for use without requiring partial 60 withdrawal to form a chamber into which the rod may project under expansion, thus allowing of the construction of a succeeding adjacent section before the first has entirely set or completely hardened, and thereby to 65 effect material saving in time in the work.

Having the above and other objects in view, the invention consists of a dowel rod for the general purpose referred to having the novel generic and specific features of 70 construction and arrangement of parts, substantially as hereinafter described and claimed.

The preferred form of the dowel rod is illustrated in the accompanying drawing, in 75 which:

Figure 1 is a longitudinal sectional view of the rod;

Figure 2 is a view of the rod shown in 80 position for use, and

Figure 3 is a face view of a metal abutment adapted for use in connection with the dowel rod, for instance, in the formation of roadbeds.

In this drawing 1 represents a rod, preferably of iron, circular in cross section, and of any diameter suitable for use in the position in which it is to be placed. One end of the rod projects into a hollow cylindrical end piece or cap 2, the opening in which is 85 of a diameter and length to receive the end of the rod and permit it free sliding movement when the rod or slabs in which it is contained, are lengthened or shortened by reason of being heated or cooled. One end 90 of the cap or end piece is closed, and projecting from the outer face of the cap is a projection of such form that when embedded in concrete or the like the cap will be held against lateral movement. The projection may, as herein shown, be in the form 95 of a flange 3 extending outwardly around the closed end of the cap or end piece.

The cap or end piece has extending through its body an opening in which is placed a 105 pin 4. The end of the pin projects into the interior of the cap or end piece at a point removed from the closed end of the cap, and forms a stop by which the distance which the end of the rod 1 initially projects into 110 the cap is determined. The pin is preferably of lead or other soft material, allow-

ing of its being sheared by the end of the rod when the latter, after being placed in position to abut against the pin, is lengthened by expansion of itself and of slabs in which it is contained.

In placing the rods, made as described in place for use, they are first coated with some substance which will adhere to them and form a lubricant to facilitate their lengthening or shortening under changes in climatic conditions. For this purpose heavy oil, tar, tar paper, or a similar substance may be employed. The caps or end pieces are then applied to the rods with the ends of the latter bearing on the pins, and the rods are passed through the openings 5 in the metal abutment 6 and caused to project beyond the outer face of the abutment which is placed in position to give form to the end of a section of road under construction, and also through a filler 7 of tar or tar paper or other material which is permanently held between the ends of adjacent completed sections, as usual in such constructions. The rods with the caps applied to them extend in suitable positions into the section being formed, and the concrete is tamped around them. After allowing the material to set for a short time, the bulkhead is removed from the rods and the material of a succeeding section is tamped around the projecting ends of the rods.

Inasmuch as when the caps or end pieces are applied to the rods, the correct initial positions of the rods with their ends spaced from the ends of the caps is insured by reason of the contact of the ends of the rods with the pins which project into positions to engage them, no manipulation of the rods is required. Therefore, not alone are the proper positions of the parts to allow expansion or contraction of the rods or of the slabs in which they are contained, assured, but the second section of the roadbed may be proceeded with after only partial setting of the first section, thus effecting great economy in time of workmen. The pins by which the distance of introduction of the rods into the caps is determined, being of soft mate-

rial, offer no substantial resistance to the lengthening of the rods, and are readily sheared when under a rise in temperature the rods lengthen or are forced to move through expansion of slabs.

In practice it has been found that joints formed by the use of dowel rods of the form described, between concrete sections, are maintained for an indefinite period. The lubricant applied to the rods being encased in the concrete is not liable to deteriorate, and, therefore, as the rods can expand longitudinally, buckling liable to injure the structure to which they are applied is impossible. The caps or end pieces being closed, no obstruction tending to confine the ends of the rods can enter. The caps, being firmly held in proper relation to the rods, furnish permanent chambers extending beyond the ends of the rods, in which the rods may freely move when necessary to prevent their distortion.

I claim:

1. A dowel rod for the purpose specified, consisting of a metal bar, a cap of rigid material having a chamber therein receiving one end of the rod, and means for limiting the distance which the rod is initially introduced into the cap. 75

2. A dowel rod for the purpose specified, consisting of a metal bar, a cap of rigid material having a chamber therein receiving one end of the rod, and a soft metal projection extending into the cap and by which the distance which the rod is introduced into the cap is limited. 80

3. A dowel rod for the purpose specified, consisting of a metal bar, a cap of rigid material having a chamber therein receiving one end of the rod, the exterior of the cap being provided with a projection adapted to be embedded in concrete or the like for holding the cap permanently in position in use, and a soft metal projection extending into the cap, and by which the distance which the rod is introduced into the cap is limited. 90

In testimony whereof I affix my signature.

EDWARD A. MARYE.
